CLAIM

The ornamental design for a combined foaming brush and housing, as shown and described.

DESCRIPTION

FIG. 1 is a perspective view of the combined foaming brush and housing;

FIG. 2 is a side view thereof, the front, back and other side being mirror images;

FIG. 3 is a top view thereof; and,

FIG. 4 is a bottom view thereof.

(Continued)

The dot-dot-dashed lines in FIG. 4 show portions of the housing that form no part of the claimed design.

1 Claim, 1 Drawing Sheet
